UNITED STATES PATENT OFFICE.

HARRY WARD LEONARD, OF BRONXVILLE, NEW YORK; CAROLYN G. LEONARD, ADMINISTRATRIX OF SAID HARRY WARD LEONARD, DECEASED, ASSIGNOR TO H. WARD LEONARD, INCORPORATED, A CORPORATION OF NEW YORK.

HEADLIGHT.

1,263,080.

Specification of Letters Patent. Patented Apr. 16, 1918.

Application filed March 23, 1914. Serial No. 828,579.

To all whom it may concern:

Be it known that I, HARRY WARD LEONARD, a citizen of the United States, residing at Bronxville, in the county of New York and State of New York, have invented certain new and useful Improvements in Head-lights, of which the following is a full, clear, and exact specification.

My invention relates to methods and means for the control of lights, and is applicable to head-lights on motor cars, street cars, interurban cars, locomotives, boats, and in various other instances.

The principal object of my invention is to provide means for the control of lights of this character whereby under certain conditions the full brilliancy and penetrating character of the light may be used and under other conditions the light may be reduced in its dazzling and penetrating effect, and yet be available to give a diffused, softened character of light, thus obtaining a light which is efficient, unobjectionable and economical under different conditions of practice, and to accomplish this result by the provision of simple, compact and conveniently operated means.

In the head-lights used upon motor cars, for example, there are customarily provided polished reflectors of approximately parabolic form with an incandescent lamp or its equivalent, so placed that the light or filament is at or near the focus of the parabola. Such lamps give a powerful beam of light for illuminating the road ahead of the motor car. This powerful beam of light has a dazzling effect upon drivers of vehicles coming toward the motor car from the opposite direction and upon people and animals which the car is approaching. The blinding effect of such a dazzling light is dangerous and objectionable, and may in some instances be injurious to the eye-sight of persons subjected to it. This powerful beam of light, however, is desirable and effective for illuminating the empty road ahead under ordinary conditions. However, it is not satisfactorily effective in going around curves, or in going over undu-

lations in the road-surface, because there is not sufficient diffusion of light at a wide angle near the car. The powerful beam of light is not satisfactorily effective under various other conditions such as when the car is passing through fog, snow, rain, or smoke, or when the front glass of the head-light becomes coated with snow, or drops of water in storms.

In order to overcome these difficulties, it is desirable that the operator of the car be enabled to quickly and conveniently change the character of the light and adapt it to suit the varying conditions as they arise without the necessity of stopping the car. For example, if two motor cars are approaching each other, it is desirable that the powerful light be modified so as to be non-dazzling to the operators of the cars when about to pass each other, and also so that the road in the vicinity of the two cars shall be well illuminated. Various other conditions arise where it is desirable to quickly and conveniently change the character of the light to the most advantageous for the particular circumstances. The above statements apply substantially to other applications of my invention than to motor cars, such as street cars, interurban cars, locomotives, boats, aeroplanes and other moving vehicles.

Many municipalities and other legislative bodies have passed laws and rules prohibiting or regulating the use of the ordinary head-light on account of the annoyance, confusion and danger which these powerful lights cause. Although the non-use of these powerful lights tends to reduce the risk to other users of the high-way, the risk to the car and to its occupants with no head-light is greatly increased, because the usual small lamps do not sufficiently light the high-way to enable the driver to drive with adequate safety. It is also sometimes desirable to enable the operator to operate warning lights at the head of the car when the car is standing still or moving slowly.

My invention overcomes all the above stated difficulties and accomplishes the de-

sirable results above mentioned as well as having other advantages. This result is also obtained by low additional first cost, small weight, small space, small consumption of energy and is adapted to be conveniently installed upon existing forms of head-lights.

One embodiment of my invention is illustrated in the accompanying drawings where in Figure 1 is a front view of a head-light 10 with the parts in position to permit the light to have its full power; Fig. 2 is a similar view with the parts in position to reduce and diffuse the light; Fig. 3 is a vertical cross-section of a head-light, the sections being to one side of a central section; Fig. 4 is a front view showing the controlling mechanism, some parts not being shown for simplicity; Fig. 5 is a plan view of the controlling mechanism; Fig. 6 is a detail sectional view; Fig. 7 is a diagram of connections; Fig. 8 is a plan view of a lamp with the outside casing removed showing a modified form of controlling mechanism; and Fig. 9 is a similar view showing a different 25 position of the parts.

The front glass of a head-light is indicated at 1 and an outside casing of the head-light is shown at 2. The lamp is shown as an incandescent lamp 3 having its filament at or near the focus of a parabolic reflector 4, but it is of course understood that the reflector and lamp may be of other suitable forms. Within the lamp frame and in front of a lamp, I place suitable material in sheet 30 form so arranged as to form no obstruction to the light in one position and to be movable to form a screen in front of the lamp so that practically all of the light has to pass through the sheet material and thus reduce its power and diffuse the light to give 35 a general illumination without any dazzling effect. In accomplishing this result, I preferably use four sections of the sheet material, two co-operating to make a half disk 40 and the other two co-operating to make the other half disk; but the number of sections may be as desired to suit particular conditions according to the preference of the designer.

I prefer to use sheet material similar to celluloid, but may use cloth, paper, mica, glass, or any other form of suitable material, and there may be instances in which the material will not be in sheet form. I prefer 50 to have the sections made of colored material and have found that an amber colored material of celluloid, or the like, gives good results; pale green is also desirable. In some cases, different colors may be used in the different lamps and sometimes the sections may be of different colors. For obtaining the desired softening and diffusion 55 of the light and to reduce the dazzling effect, I prefer to have the surface of the sheets

finished so as to resemble the surface of ground glass. Objects seen through such a translucent medium will be blurred and a parallel beam of light when forced to pass through such a medium will be very much diffused and softened so that it will not be dazzling to the eyes of a person looking through it at a powerful light.

While many different forms of construction may be employed, I prefer to provide within the lamp frame and in front of and on each side of the lamp supports adapted to carry two sections. Thus in the drawings, the reflector 4 is shown as perforated for the purpose of forming a bearing and support for parts which in turn carry the sections of sheet material. Extending through perforations in the upper part of the reflector are shown parts 5 in tubular form from each of which a curved support or rib 6 extends, which embraces, or to which is fastened a section 7 of sheet material, which extends from the vertical pivotal support toward the side of the reflector. The lower end of each rib 6 is shown connected with a tubular part 8. Each of the tubular parts 5 forms a support and bearing for a rod 9, which rod extends downwardly through the tubular parts 8 and through a perforation in the lower part of the reflector, which thus serves as a support and bearing for rods 9. Connected with each of the rods 9 are shown horizontally extending ribs 10, which embrace or have attached thereto sections 11 of sheet material, which extend from the supports to the middle of the reflector when in closed position. The ribs for supporting the sheet sections may be of any suitable form or material for adequately supporting the sheet sections, and the sheets may be attached thereto in any suitable manner.

It will be apparent that when the parts supporting the sections 7 are turned upon a vertical axis and 90° from the positions as shown in Figs. 2 and 4, the sections will assume positions in vertical planes parallel with the rays of light of the reflector as shown in Fig. 1, and similarly when the supports for the sheet sections 11 are turned 90° upon the vertical axis they will be thrown from the position shown in Figs. 2 and 4 to that shown in Fig. 1 parallel with the rays from the reflector. In the position shown in Figs. 2 and 4, the sheet sections form a disk substantially preventing the emission of all light from the lamp, except that which is forced to pass through the sections, whereas in the position shown in Fig. 1 the sections are in vertical planes parallel with the beam of light from the reflector and offer no substantial obstruction to such rays.

For accomplishing the movement of the

four sections so as to have them at one time across the beam of light and at another time parallel to the beam, I preferably use an electromagnet, the movable armature of which is so mechanically related to the sections that when one winding or a part of the winding is energized all of the sections will be moved to their edgewise position. The winding causing the movement may then be deenergized and the sections held in edgewise position by spring action, thus requiring no further consumption of electric energy after the movement has taken place. When it is desired to move the sections in position across the beam of light, another winding or another portion of the winding of the magnet will be energized to cause movement of the armature so as to rotate the sections 90° when the winding may then be deenergized and the sections will be held in the new position by spring action. Referring to the drawings, a controlling magnet is shown at 12 having two windings 13, 13'. A single core for the two windings is shown at 14 and is adapted to be moved to the position shown in dotted lines in Fig. 5 when the winding 13 is energized and to be moved a short distance to the right of the position indicated when the winding 13' is energized. The magnet is shown in this instance as being located between the upper portion of the reflector 4 and the outside casing 2, and approximately midway between the vertical axes about which the sheet sections turn. To each end of the iron core 14 is secured a rod or strip 15, the outer end of which is bent as shown in the drawings and connected to a cross piece 16. At each end of each cross piece are pivotally connected links 17. The remaining end of one link 17 is pivotally connected to an extension 18 from the tubular part 5 and the remaining end of the other link 17 is similarly connected to an extension 19 from the rod 9. Between the ends of the links to which the extensions 18 and 19 are connected, or between the extensions 18 and 19 is located a spring 20, which tends to draw the ends of the link and also the extensions 18 and 19 toward each other. The angular relation of the extensions 18 and 19 to the planes of the sheet sections are such that when the sections are in the closed position as shown in Figs. 4 and 5, the tension of the springs 20 serves to maintain the sections in this position by constant spring tension and hold the sections against the reflector, lamp, or specially provided stops if desired, and thus prevent any tendency of vibration or of being thrown out of their closed position by shocks or jars.

If the winding 13' be energized, the armature 14 will be shifted from the position shown in Fig. 5 to the right against the tension of the springs 20 and in this movement

the inner ends of the links 17 will be moved outwardly to some extent until the springs have been carried over the vertical axis of the supports for the sheet sections and will then move inwardly to a new position. In this movement the extensions 18, 19 and the sheet sections will be moved through an angle of approximately 90° so that in the new position the sheet sections will be brought to the open position and the springs 20 then serve to hold the sections against each other in this position, which prevents any vibration of the parts or any tendency to be thrown from this position by shocks or jars.

It is obvious that the sheet sections will be readily shifted from the closed position to the open position by momentarily energizing one of the windings of the magnet and that the reverse movement is accomplished by momentarily energizing the other windings of the magnet, and that in each of the final positions the sheet sections will be held firmly by spring action without any necessity of continuing the excitation of either of the controlling windings.

I preferably energize these magnets from the storage battery or other source of electric energy used to supply the lamps in the head-lights, but in some instances it may be desirable to use a different source. For controlling the energization of the windings I preferably employ a two-way spring actuated switch normally biased to open position and closable by the operator to temporarily energize one or the other of the controlling windings.

A diagram of connections is shown in Fig. 7 wherein the head-light lamps are shown at 3, one on each side of the car, and the controlling windings for controlling the movement of the sheet sections in each lamp are indicated at 13, 13'. A storage battery 21 is shown in this instance as the source of electric energy for the lamps 3 as well as for the controlling windings. Upon a dashboard 22 of the car, or at any location convenient to the operator, is mounted a switch 23 for connecting the head lights in parallel with each other to the battery 21 and there is also mounted a two-way switch 24, having springs 25 tending to hold the switch normally in open circuit position. By pressing one end of the switch 24 a circuit is closed from one terminal of the battery through the switch and through the windings 13 back to the other terminal of the battery. When the switch 24 is depressed at its opposite end, the circuit is closed from the terminal of the battery through the switch and through the controlling windings 13' back to the other terminal of the battery. It is obvious that by momentarily closing the switch 24 to energize either the windings 13 or 13' as desired, the sheet sections will be shifted to either the open or 130

closed positions and will be held in either of these positions by spring action after the release of the switch 24.

It is obvious that various modifications of the electromagnetic controlling means above disclosed may be used without departing from the scope of my invention, and that in some instances the sections may be moved directly by hand or by cords, wires, or rods conveniently located for manipulation by the operator from the seat of the car; also the control may be accomplished by pneumatic or hydraulic means or a spring motor may be used to shift the movable sections, the operation of the spring motor being controlled by any well-known means from the driver's seat.

Figs. 8 and 9 illustrate a modified form of construction of controlling means for moving the sections of sheet material, the controlling means in this case being manually operated. The figures show a plan view of the controlling means, the outer casing of the lamp being removed, and the parts corresponding to those already described are similarly numbered. The front part of the reflector is shown at 4, and the sections of sheet material 7 and 11 are indicated in dotted lines, being the same in construction and mounting as already described. The extensions 18, 19 from the supports of the sheet sections 7 and 11 in this modified form are pivotally connected to a yieldable wire frame 26, an extension 27 from which is connected to one end of a spring 28. One end of the spring is connected to a bracket 29 fixed to the outside of the reflector 4. At the opposite end of the spring is connected a flexible cord, chain or shaft, 30, which passes through a protecting and supporting tube 31 to a handle 32, which may be located at any point convenient to the operator, at or near the dash-board of the car, or at the side of the seat, or any other convenient point. In the position shown in Fig. 8, the sheet sections are shown in closed position and are so held by the tension of the spring 28 and yieldable extensions of the wire frame 26. When it is desired to place the sheet sections in open position the operator pulls open the handle 32 against the tension of the spring 28, which results in turning the extensions 18 and 19 and the sheet sections through an angle of 90°, bringing the latter to the open position as shown in Fig. 9, the yieldable extensions of the wire frame 26 tending to hold the sheet sections in open position. The handle may be held in this position by a hook, latch, or other convenient means so as to maintain the sheet sections in open position until the handle is released, when the spring 28 will then throw the sheet sections to the closed position as shown in Fig. 8. When the element 30 is sufficiently

rigid, the spring 28 is unnecessary as the element 30 may then be pushed to move the sheet sections to closed positions.

In addition to the application of my invention to head-lights, there are various other applications such as to lamps used for advertising purposes, stage illumination, photography, illumination of rooms, and for signals and the like.

It will be understood that many modifications may be made in all of the various features of my invention without departing from the scope thereof.

Having thus described my invention, what I declare as new and desire to secure by Letters Patent of the United States is:—

1. In a head-light, a parabolic reflector, a lamp within said reflector, a plurality of sections of light diffusing sheet material also within said reflector in front of said lamp, pivot shafts carrying said sections and extending through the reflector wall, means outside said wall to actuate said shafts and turn the sections more or less edgewise or transverse to the beam of light and automatic means to hold said sections in any one of a limited number of definite positions.

2. In a head-light, a parabolic reflector, an outside casing around the reflector and spaced therefrom, a lamp within said reflector, sections of light diffusing sheet material in front of said lamp and also within said reflector and means located between the reflector wall and the outside casing adapted to turn said sections more or less edgewise or transverse to the beam of light.

3. In a head-light, a parabolic reflector, an outside casing around the reflector and spaced therefrom, a lamp within said reflector, sections of light diffusing sheet material in front of said lamp and also within said reflector, means located between the reflector wall and the outside casing adapted to turn said sections more or less edgewise or transverse to the beam of light and to hold said sections in any one of a limited number of definite positions.

4. In a head-light, a parabolic reflector, a lamp within said reflector, a wall of transparent material across the front of said reflector, a plurality of sections of light diffusing sheet material between the said lamp and the said front wall, parallel shafts attached to said sections at respective edges thereof, and means to swing the said sections on said shafts to an edgewise position in pairs relatively to the beam of light, or apart transversely to said beam.

5. In a head-light, a parabolic reflector, a lamp within said reflector, a transverse shaft within said reflector on each side of the axis of the reflector, sections of light diffusing sheet material attached at their

- respective edges to these shafts, said sections lying normally edgewise to the beam of light and directed away from the lamp, and means under the control of an operator 5 for turning said sections about said shafts so as to bring their distal edges to meet across the axis of the reflector.
6. In a head-light, a parabolic reflector, a lamp within said reflector, a pair of closely 10 adjacent shafts across the reflector on each side of its axis, a section of light diffusing sheet material attached by an edge thereof to each such shaft, said sections comprising the segments of a circular disk and being 15 normally directed away from the lamp edgewise to the beam of light and means to turn the two shafts of each pair simultaneously in opposite directions and thereby turn the sections across the reflector so that the segments of the circular disk will form a substantially complete closure across the parabolic reflector.
7. In a head-light, a parabolic reflector, a lamp within said reflector, a plurality of 20 parallel shafts across said reflector in front of said lamp, said shafts being arranged in pairs, those of a pair close together, sections of light diffusing sheet material with their respective edges supported by said shafts 25 and normally directed edgewise to the beam of light away from said lamp and means to turn said shafts simultaneously in alternately opposite directions so as to swing
- the sections of each pair away from each other and in a position transverse to the beam of light.
8. In a head-light, a parabolic reflector, an outside casing around the reflector spaced therefrom, a lamp within said reflector, sections of light diffusing sheet material in front of said lamp and also within said reflector, shafts carrying said sections and extending through the reflector wall, and electromagnetic means located between the reflector wall and the outside casing adapted to act on said shafts.
9. In a head-light, a parabolic reflector, an outside casing around the reflector spaced therefrom, a lamp within said reflector, sections of light diffusing sheet material in front of said lamp and also within said reflector, shafts carrying said sections and extending through the reflector wall, electromagnetic means located between the reflector wall and the outside casing adapted to act on said shafts and automatic means in the same location to hold said sections in either the edgewise or transverse positions.

In testimony whereof I affix my signature so in presence of two witnesses.

HARRY WARD LEONARD.

Witnesses:

LEONARD KEBLER,
CAROLYN G. LEONARD.
